UNITED STATES PATENT OFFICE

104,840

DESIGN FOR A CHEST OF DRAWERS

Abraham G. Feldman, Chicago, Ill.

Application April 29, 1937, Serial No. 69,057

Term of patent 3½ years

To all whom it may concern:

Be it known that I, Abraham G. Feldman, a citizen of the United States, residing at Chicago, in the county of Cook, and State of Illinois, have invented a new, original, and ornamental Design for Chests of Drawers, of which the following is a specification, reference being had to the accompanying drawing, forming part thereof.

The figure is a perspective view of a chest of drawers, showing my design.

I claim:

The ornamental design for a chest of drawers, as shown.

ABRAHAM G. FELDMAN.
